UNITED STATES PATENT OFFICE.

SAMUEL P. HUNTINGTON, OF NEW HAVEN, CONNECTICUT, ASSIGNOR, BY MESNE ASSIGNMENTS, TO THE RECORDING REGISTER & FARE BOX COMPANY, OF NEW HAVEN CONNECTICUT, A CORPORATION OF CONNECTICUT.

FARE-REGISTER.

1,144,475.

Specification of Letters Patent. Patented June 29, 1915.

Application filed August 8, 1908. Serial No. 447,489.

To all whom it may concern:

Be it known that I, SAMUEL P. HUNTINGTON, a citizen of the United States, and resident of New Haven, in the county of New Haven and State of Connecticut, have invented certain new and useful Improvements in Fare-Registers, of which the following is a full, clear, and exact specification.

This invention comprises improvements in fare registers, counting machines, and similar mechanism, the object being to improve the construction, arrangement and certainty of operation of such machines, and particularly to provide for setting and interlocking the various parts in such a way as to insure correctness and a proper sequence in their operation, and to prevent certain parts from being operated improperly during the operation of other parts.

20 These improvements are herein shown to be embodied in a fare register of the class employed on street cars for registering the fares collected.

Figure 1 is a front view partly in section taken through the axial center of the mechanism, showing the resetting mechanism, and parts of the advancing or registering mechanism in their free or unlocked position. Fig. 2 is a fragmentary view showing portions of the mechanism of Fig. 1, with the registering arm locked and the resetting mechanism moved partway to its operating position. Fig. 3 is a view similar to Fig. 2, but showing the resetting parts in their operating position. Fig. 4 is an underneath view projected from Fig. 1. Figs. 5, 6 and 7 are front views showing in different positions the locking devices for controlling the lengthwise position of the resetting shaft. Figs. 8, 9 and 10 are end views showing in three different positions one of the counters or registering dials illustrating the operation of resetting it to zero position. Fig. 11 is an end view projected from the left hand side of Fig. 6. Fig. 12 is a front view showing a modified form of spring for moving the resetting shaft in its axial or lengthwise direction.

The mechanism herein shown may be connected or associated with any of several well-known forms of registering mechanism. In the case of fare registers, it would generally be contained in an inclosing frame 1, having a glass face with an apertured mask

for exposing to view the numerals and other characters or symbols at their proper positions. The counters or fare wheels 2, 3 and 4 are mounted for rotation and axial movement upon the shaft 10, and are provided upon their peripheral surfaces with numeral 55 characters 0 to 9 inclusive, which are exposed to view one at a time, through suitable apertures in the masked face of the register. These three counters represent the units, tens and hundreds, respectively, although obviously a larger or smaller number of counters may be employed, according to the requirements. These counters are herein shown to be attached to armed or webbed spiders 6, 7 and 8, which are free to 60 rotate upon the resetting shaft 10, which is mounted to rotate and slide endwise in suitable bearings in the side frames 11 and 12. The units spider 6 has fixed upon it the gear 14, meshing with the driving gear 15, which 65 in turn has fixed to it the ratchet wheel 16. The gear and ratchet 15 and 16 are mounted upon a shaft 17, journaled in any convenient way in the frame, and the ratchet is advanced by any well known pawl mechanism, 70 worked by the operating arm 20, which is connected in any well-known or suitable way with the operating cords or rods of the car or vehicle in which the register is used, so that one stroke of the operating arm 20 75 serves through the ratchet 16 and gears 15 and 14 to turn the units counter one-tenth of a rotation. The counters 2, 3 and 4 are provided or connected with any suitable means 80 for advancing the tens and hundreds counters one step at the completion of each rotation of their respective lower counters, so as to "carry" the tens and hundreds to their 85 respective counters. In the present instance this connecting mechanism is a modification 90 of the well-known Geneva stop mechanism, consisting in each case of a star wheel 22 and a gear 23 mounted for rotation upon a shaft 24. The spiders 7 and 8 of the tens and hundreds counters 3 and 4 are provided with 95 gears 26 and 27, which when the parts are in the registering or advancing position shown in Fig. 1, are in mesh with the gears 23 of the Geneva stop mechanism, and are free to rotate upon the shaft 10. While thus 100 in mesh with the gears 23 the counters are controlled as already described as to their 105 registering sequence of operation. They are

drawn endwise out of mesh as shown in Fig. 3, to enable the counters 2, 3 and 4 to be reset to their zero position, during which time the Geneva stop wheels are locked 5 against rotary movement by means of uninterrupted portions of the cylindrical surfaces of the spiders 6 and 7, which are moved into the plane of the stop wheels by the endwise movement of the counters, that movement carrying the recesses 92 out of the plane of the stop wheels.

The main shaft 10 is the central element through or by which the different devices of the present invention, and their respective functions are connected, associated and controlled. When in its resting position shown in Fig. 1 the shaft serves as an axial support upon which the counters 2, 3 and 4 rotate in the performance of their registering functions, moved by the operating arm 20 and its connected train of mechanism. The main shaft 10 also serves to reset the counters uniformly to zero from the various positions in which they are left 15 at the conclusion of the registering operations, serving also in connection with that operation to lock the registering and Geneva stop mechanisms out of operation. For the performance of these 20 various functions the shaft is compelled to move in a particular manner. It is first moved lengthwise in the direction of its axis from the position of Fig. 1, to that of Fig. 3, then turned one complete rotation in 25 the direction of the arrow shown in Fig. 3, then returned in the opposite lengthwise or axial direction to the position shown in Fig. 1. Means are provided for insuring the 30 correct direction and sequence of these movements in the sense that they permit the shaft and its parts to be moved only in the prescribed direction and sequence.

The main shaft 10 is mounted for both axial and rotary movement in the side 35 frames 11 and 12 and is provided with a knob or handle 29 by means of which the shaft may be manually operated from the outside of the casing, the operation being simply to draw the shaft endwise until it 40 reaches the point where it can be rotated, then rotate it one complete turn, and then push it back lengthwise or axially to its former position, this simple movement being all that is required to reset the counters to zero, and to perform all other required functions of interlocking and safeguarding the complete operation of the machine. In the machine from which the accompanying drawings are made the main 45 shaft 10 serves also to actuate the recording mechanism. But that feature forms no part of the present invention, and hence need not be further described or referred to herein.

60 Axial movement of the shaft is permitted

only when the shaft is in the rotary position shown in Fig. 1, and rotary movement is permitted only when the shaft is in the axial or lengthwise position shown in Figs. 3, 5, 6 and 7. That rotary position is determined by means of a pin 30 fixed in the shaft and engaging in a slot or splineway 31 in the side frame 12, it being necessary to draw the pin 30 entirely out of the splineway to the position of Fig. 5 before the shaft can be rotated. When drawn to the position of Fig. 5 the shaft is prevented from being pushed back again by means of the pawl 69 pivoted at 70, engaging with the shoulder 72 of the collar 68 appurtenant to the shaft 10. The only movement then possible for the shaft is to rotate it in the direction of the arrows shown adjacent to the shaft 10. During this rotation the pin 30 is carried out of register with the slot 31 and rests against the end of the hub 75 as shown in Fig. 6, thus preventing the return axial movement of the shaft until it has completed its rotation, carrying the pin 30 again into register with the slot 31. The 70 rotation of the shaft carries the shoulder 72 away from the pawl 69 as shown in Figs. 6 and 11, and by its continued movement carries the pawl to its reversely inclined position shown in Fig. 7, by means of the inclined surface 73 of the collar. As the shaft is returned axially toward the left from the position shown in Fig. 7 to that of Fig. 1, the collar 68 rides past the pawl 69, the end of the pawl dropping behind the shoulder 74 on the way, so as to prevent the shaft being moved axially to the right after it has once fairly started upon its return movement toward the left, the completion of which carries the shoulder 72 of the collar entirely past the pawl 69, allowing it to drop again to its intermediate resting position shown in Fig. 1, where it is yieldingly held by its spring 71.

The shaft 10 is compelled to rotate in the direction indicated by its adjacent arrows, being prevented from rotating in the opposite direction by means of its splined connection with the ratchet 32 journaled on the side frame 11, and through which the shaft slides, that ratchet coacting with a pawl 33 pivoted on the side frame 11 to prevent backward rotation of the shaft.

Means are provided for interlocking the operating arm 20 of the register and the resetting shaft 10 so that neither can be operated except when the other is resting in its inoperative position shown in Fig. 1. The locking lever 35 is pivoted at 36 upon the side frame 11 in such a way that its locking end is swung in front of the operating arm 20, as shown at the position in Fig. 1, by the initial axial movement of the shaft 10. Or, when in that position, the operating arm 20 can be swung in front of the locking 130

arm 35, thus reciprocally locking each other, the one first in action locking the other out of action. The opposite end of the locking arm 35 is forked as shown in Fig. 4, or provided with suitable pins or arms 37, which engage on opposite sides of the collar 38 fixed on the resetting shaft 10, so that the locking arm is moved by the lengthwise movements of the shaft 10. That locking movement takes place during the initial movement of the shaft to the position shown in Fig. 2 and before the counter gears 26 and 27 are drawn out of mesh with their coacting gears 23 to release them for the resetting operation, it being desirable thus to lock the operating mechanism in advance of the disengagement of the counters.

The clutch devices for resetting the counters 2, 3 and 4 to zero consists of clutch dogs or pins 40 fixed in the shaft 10, and of bell-crank clutch arms 41 pivotally mounted on the spiders 6, 7 and 8, or other suitable appurtenances of the counters 2, 3 and 4. In the present instance they are shown to be mounted upon studs 42 and are pressed by means of springs 43 to their resting position against the stop pins 44, also appurtenant to the spiders 6, 7 and 8, as shown in Figs. 8. When the shaft 10 is in its resting or inoperative position shown in Fig. 1 the pins 40 are out of the plane of the arms 41, leaving the latter free to revolve with their respective spiders on the shaft 10 during the registering operations. As the shaft is drawn axially to the right, the initial movement engages the clutch devices of the shaft and counters by carrying the pins 40 into the plane or zone of movement of the arms 41, while the counters remain in position, with their gears 26 and 27 still in mesh with their driving gears 23, being disengaged therefrom only by the continued axial movement of the shaft 10, the pins 40 and the counters 2, 3 and 4.

The axial movements of the counters 2, 3 and 4 relative to the axial movement of the shaft 10, whereby the gears 26 and 27 are kept in mesh with the gears 23 while passing from the free position of Fig. 1 to the clutched position of Fig. 2, are positively controlled by means of a cam-like thrust latch 48, which is pivotally mounted at 49 in the shaft 10, preferably lying in a mortise 50 in the shaft, as best shown in Fig. 4, and also serving as a spline between the shaft 10 and ratchet 32. The swinging movement of this latch is jointly controlled by the shaft 10 through the pivot 49 and by the adjacent portion 51 of the side frame 11, which engages like a gear tooth in a suitable notch in the latch 48, serving to swing the latch to the desired positions, as illustrated in Figs. 1, 2 and 3. In the initial movement of the shaft from the position of Fig. 1 to that of Fig. 2 the swinging end of the latch 48 by

bearing against the gear 14 holds back the train of counters, serving the double purpose of keeping their respective gears in mesh with the gears 15 and 23, and at the same time enabling the driving pins 40 to overtake and pass into the plane or zone of the cranked arms 41, thus engaging the clutch devices of the shaft and counters. From the position shown in Fig. 2 to that of Fig. 3 the latch remains practically unchanged, locking the shaft 10 and the train of counters in their clutched relation, and continuing so while rotating the counters to their zero position. At the completion of the resetting rotation of the shaft 10 it is moved axially back toward the left, and in passing through the position shown in Fig. 2 to that of Fig. 1 the latch 48 pushes the train of counters into mesh with their respective gears 15 and 23 before disengaging the driving pins 40 from the crank arms 41.

The coöperation of the pins and arms 41 during the resetting operation is best illustrated in Figs. 8, 9 and 10. The pins 40 engage only with the arms 41 of those dials which are not already at their zero positions, and carry them to that position by means of the said arms. The dials which are already resting at their zero position are not moved. This is illustrated in Fig. 10, in which the pin 40 when moved lengthwise moves in front of the arm 41, and moves away from that arm while making its revolution. At the completion of its revolution, however, it moves against the rearward side of the arm 41, carrying it to the position shown in Fig. 9, and upon moving the shaft 10 axially to the position of Fig. 1, the arm 41 is released and falls back to the position shown in Fig. 10. In the case of a dial which has during the registering operations been moved away from its zero position, as illustrated in Fig. 8, the arm 40 in moving lengthwise into the plane or zone of the arm 41 is carried behind that arm, and at some time in its revolution overtakes that arm, as shown in Fig. 8, carrying it thence to its zero position shown in Fig. 9, at which time the counter, being stopped at its zero position, the arm 40 is swung forward by the pin 40 against the pressure of the spring 43, to enable the pin 40 to complete its revolution at which time the shaft 10 upon moving axially to its position of Fig. 3 releases the arm 41 and allows it to return to the position shown in Fig. 10.

The Geneva stop devices, in addition to connecting the counters for their proper advancing movement during the registering operations also serves as zero stops for the counters during their resetting operation, as shown in Figs. 9 and 10. During the advancing movement, the parts being in the position shown in Fig. 1, the recesses 92 are in the plane of the star wheels 22 and regis-

ter with the points of these star wheels at the "carrying" or transferring position, permitting the corners of the star wheels to rotate to advance the next counter one step. 5 But, during the resetting operations, when the counters are drawn to the position shown in Fig. 3, the recesses 92 of the spiders are carried out of the plane of the star wheels, so that an uninterrupted cylindrical portion 10 of each spider is presented to its associated star wheel. This uninterrupted cylindrical surface 53 of the spiders 6 and 7 fitting against corresponding concavities 54 on the star wheel 22, prevent the star wheels from 15 turning so that the pins 55, appurtenant to the counters by colliding against the star wheels, stop the counters at their zero positions shown at Figs. 9 and 10.

In moving the shaft back to the position 20 of Fig. 1 to that of Fig. 3 the locking lever 35 is moved away from in front of the operating arm 20, leaving the latter free to operate the register.

It is desirable to provide a spring or its 25 equivalent for yieldingly holding the shaft 10 axially to its position shown in Fig. 1, to prevent it from being moved away from that position by jarring movements, in the operation of the register. In registers of this 30 character such springs are or may be coiled around the shaft 10 between the gear 14 and the side frame 11. But since in the present instance that space is occupied by the latch 48 the spring is applied elsewhere. In the 35 arrangement shown in Figs. 1 to 4 inclusive a spring arm 58 is pivoted at 59 to the side frame 11, and bears against the outer side of the locking lever 35, its lower end being connected with a spring 60 attached at 61 to the 40 register back plate or frame. In the modification shown in Fig. 12 a spring 63 is attached to the side frame 11, and bears against the outer side of the collar 38. A roller 64 or other suitable anti-friction device may be employed between the 45 spring and the collar. In either case the shaft is moved axially against the pressure of this spring until the pin 30 is drawn out of the end of the slot 31, after 50 which and during the turning movement of the shaft the pin rests against the end 65 of the surrounding hub of the side frame 12. At the completion of the rotation the pin again registers with the slot 31, and is carried back to its resting position of Fig. 1 by the spring, assisted if necessary by the hand 55 of the operator.

The consecutive operation of the entire mechanism is as follows:—At the end of a 60 trip or half trip, or at any other time when it may be desirable to reset the counters to zero, with the operating arm in the position shown in Fig. 1, the operator, by means of the knob or handle 29, draws the shaft 10 to

the right, as viewed in that figure, thereby 65 moving the clutch pins 40 into clutching relation to the arms 41 of the counters. During the same initial movement the thrust latch 48, by being swung to the position shown in Fig. 2, holds back the train of 70 counters from moving with the shaft, thus maintaining the gears 14, 26 and 27 in engagement with their driving gears 15 and 23. The initial axial movement of the shaft also moves the locking arm 35 in front of 75 the operating arm 20, thus locking the latter and its connecting registering mechanism out of operation. Arriving at the position shown in Fig. 2 the counters are latched in clutched relation to the pins 40 80 by the latch 48 and continue in that position while being moved by the continued axial movement of the shaft to the position shown in Fig. 3, this continued movement carrying the gears 14, 26 and 27 out of mesh with their 85 driving gears 15 and 23, leaving the counters free to be turned with the shaft 10, as the latter is rotated in the direction of the arrow. During this rotation the clutch pins 40 pick up the respective counters 2, 3 and 90 4, according to the position in which they are left at the conclusion of the registering operation, and carry them to their zero position, at which they are stopped by their pins 55 engaging with the star wheels 22, as 95 illustrated in Fig. 9. The spring-pressed arms 41 are held yieldingly as shown in that figure, to permit the rotation of the shaft to be completed, at which point the pin 30 is brought into register with the splineway 31 100 and is moved by the spring 60 or 63 axially back to the position of Fig. 1, aided if necessary by the hand of the operator. During this return axial movement of the shaft the counters 2, 3 and 4, being latched by the 105 latch 48 against the pins 40, are carried axially back to the position shown in Fig. 2, in which the gears 14, 26 and 27 are carried into mesh with their driving gears 15 and 23. From this position the latch 48 is opened 110 by the continued axial movement of the shaft to the position shown in Fig. 1, thus allowing the shaft to carry the clutch pins 40 out of clutching relation to the arms 41. The completion of this movement also carries the locking arm 35 away from in front of the operating arm 20, thus releasing the 115 registering mechanism and enabling it to be operated for the succeeding trip or half trip, at the end of which, or at any other 120 desired time, the counters may again be reset to zero by repetition of the operation just described.

The collar 68 is herein shown as a separate element, pinned to the shaft 10. This, however, is for convenience in manufacturing and assembling the parts. Obviously, the collar might be an integral part of the shaft, 125

or the surfaces which engage with the pawl 69 may be in the shaft itself, without any collar.

Many of the other parts which are herein 5 shown to be separate or separable parts are so shown for convenience in manufacture, assembling and repairs, but might be made in various other ways which will be understood by mechanics familiar with this class 10 of work. Thus, in many ways the construction and arrangement herein shown and described may be modified for various reasons or purposes, according to the skill or judgment of the designer or constructor.

15 The terms "axial" and "axially" are herein employed as concise terms for designating the movements of the various parts in the direction of their axes of rotation.

Some of the features necessarily shown 20 and described, but not claimed herein, are shown, described and claimed in the co-pending application of F. B. Kennedy, Serial No. 441,947, filed July 6, 1908.

I claim as my invention:—

25 1. In a machine of the class specified, an axially movable shaft, a member so mounted on said shaft as to permit said shaft to have axial movement relatively thereto, and means connected with said shaft and movable relatively thereto by the axial movement thereof for controlling the axial position of the member relatively to the shaft.

30 2. In a machine of the class specified, an axially movable shaft, a member so mounted on said shaft as to permit said shaft to have axial movement relatively thereto, and means movable relatively to said shaft by the axial movement of said shaft to cause said movement of said shaft to be relative to said 40 member.

35 3. In a machine of the class specified, a shaft, a member rotatably mounted on said shaft, said shaft being capable of axial movement relatively to said member, means controlled by the axial movement of said shaft for preventing rotary movement being imparted to said member in one direction, and means also controlled by the axial movement of said shaft to cause said axial movement of said shaft to be relative to said member, whereby said member is held 50 against axial movement until said means for preventing rotary movement has been actuated.

40 4. In a machine of the class specified, a shaft, a member rotatably mounted on said shaft, said shaft being capable of axial movement in unison with said member and relatively to said member, and means to hold 55 said member against axial movement during the first portion of the axial movement of said shaft and to release said member to permit it to move with said shaft during a further axial movement thereof.

5. In a machine of the class specified, a 65 shaft, a counter mounted on said shaft, said members being capable of axial movement in unison, and means operable by the axial movement of one of said members relatively to the other for altering the relative axial 70 positions of the two members.

6. In a machine of the class specified, an axially movable shaft, an axially movable counter mounted on said shaft, and means operable by the axial movement of the shaft 75 for altering the axial position of the counter relatively to the shaft.

7. In a machine of the class specified, a shaft, a counter mounted thereon, said shaft being capable of axial movement both in 80 unison with said counter and relatively thereto, a device movably mounted on and operable by the axial movement of said shaft for causing one portion of said axial movement to be relative to said counter and 85 another portion of said movement to be in unison with said counter.

8. In a machine of the class specified, an axially movable shaft, a rotary counter axially movable on the shaft, and means 90 operable by the axial movement of the shaft for holding back the counter relative to the said shaft movement.

9. In a machine of the class specified, an axially movable shaft, a counter mounted 95 for rotary and axial movement relative to said shaft, and a thrust latch operable by the axial movement of the shaft for pushing and holding back the said counter relative to the said axial movement.

10. In a machine of the class specified, an axially movable shaft, a rotary counter axially movable on said shaft, a thrust latch mounted on said shaft and controlled by its axial movement for changing the axial position of the counter relative to the shaft, and latching it in its changed position.

11. In a machine of the class specified, an axially movable shaft, a rotary counter mounted for axial movement on said shaft, 110 a thrust latch mounted on said shaft and operable by its axial movement for axially changing the counter relative to the shaft, and latching it in its changed position.

12. In a machine of the class specified, a 115 rotary and axially movable shaft, a counter mounted for rotation and axial movement on said shaft, clutch devices connected and disconnected by initial relative axial movement of the shaft and counter, for rotating 120 the counter with the shaft, external driving means for rotating the counter on the shaft, connected and disconnected by continued axial movement of the shaft and counter, and means operable by the said initial axial 125 movement of the shaft for maintaining the counter in engagement with its external driving means, and for latching the counter

and shaft during their continued axial movement while disengaging the counter from its external driving means.

13. In a machine of the class specified, an axially movable rotatable shaft, a counter axially movable on said shaft, clutch devices for rotating the counter with the shaft, engaged and disengaged by their relative axial movement, and means operable by the axial movement for effecting the said relative axial movement, and latching the counter in its clutch engaging position.

14. In a machine of the class specified, an axially movable shaft, a counter mounted for rotation and axial movement on said shaft, clutch devices for rotating the counter with the shaft, engaged and disengaged by their relative axial movement, and a latch mounted on the said shaft, and bearing against the said counter for effecting the said relative axial movement by the axial movement of the shaft, and latching the counter in its clutch position.

15. In a machine of the class specified, an axially movable shaft, a rotary counter mounted for axial movement upon the shaft, a driving device for rotating the counter on the shaft, clutch devices for connecting the counter with the shaft, and means operable by the axial movement of the shaft for maintaining the counter in engagement with its driving means during said axial movement.

16. In a machine of the class specified, a rotary counter, a shaft mounted for axial and rotary movement in the counter, driving means for rotating the counter on the shaft, clutch devices between the shaft and the counter connected and disconnected by their relative axial movement, and a thrust latch appurtenant to the shaft and operable by its axial movement for maintaining the counter in engagement with its external driving connection, while effecting the said relative axial movement of the shaft and counter to connect the clutch devices.

17. In a machine of the class specified, an axially movable shaft, a plurality of rotary counters mounted for axial movement upon and with the shaft, driving devices for rotating the counters on the shaft, clutch devices for connecting the counters with the shaft, means operable by the axial movement of the shaft for engaging the clutch devices and means carried with and operable by said axial movement for maintaining the counters in engagement with their said driving means during said axial movement.

18. In a machine of the class specified, a rotatable and auxiliary movable shaft, a plurality of counters mounted for rotary and axial movement upon the shaft, driving devices for rotating the counters on the shaft, clutch devices engaged by the axial

movement of the shaft for connecting the counters with the shaft, and means operable by the axial movement of the shaft for maintaining the counters in engagement with their respective driving means during the clutch connecting axial movement of the shaft.

19. In a machine of the class specified, a rotary and axially movable shaft, a plurality of counters mounted for rotation and axial movement upon the shaft, driving devices for rotating the respective counters on the shaft, clutch devices for connecting the counters with the shaft, and means carried with and operable by axial movement of the shaft for first connecting the counters with their respective driving means and then disconnecting the clutch devices.

20. In a machine of the class specified, a rotary and axially movable shaft, a plurality of counters mounted for axial movement upon the shaft, driving devices for rotating the respective counters on the shaft, clutch devices for connecting the counters with the shaft, and means operable by axial movement of the shaft for maintaining the counters in engagement with their driving means and meanwhile connecting the clutch devices, and for restoring the counters to engagement with their driving means before disconnecting the clutch devices.

21. In a machine of the class specified, a rotatable and axially movable shaft, a plurality of counters mounted for rotation and axial movement upon the shaft, driving devices for rotating the counters on the shaft, clutch devices operable by axial movement of the shaft for connecting and disconnecting the counters with and from the shaft, and means operable by the said axial movement of the shaft for maintaining the counters in engagement with their driving means during the clutch engaging axial movement, for maintaining the said clutch devices in engagement while disconnected from the said driving means, and for restoring the counters to engagement with their driving means before disconnecting the said clutch devices.

22. In a machine of the class specified, a registering train of counters, and means for resetting said counters, including in combination a rotatable and axially movable shaft and a yielding pawl, the shaft being provided with reversely disposed shoulders for engaging with the pawl when the latter is in oppositely inclined positions, one of said shoulders being arranged to be moved out of engagement with said pawl when rotary movement is imparted to said shaft.

23. In a machine of the class specified, a registering train of counters, and means for resetting said counters, including in combination a rotatable and axially movable shaft

- and a yielding pawl, the shaft being provided with reversely disposed shoulders for engaging with the pawl when the latter is in oppositely inclined positions and having
- 5 an inclined shoulder adjacent to the first-mentioned shoulders, said shoulders being of a width less than the circumference of said shaft, whereby the rotary movement of said shaft will first release the pawl and
- 10 then move the same into an oppositely inclined position.
24. In a machine of the class specified, a registering train of counters, and means for resetting said counters including in the combination a rotatable and axially movable shaft, and means for compelling a definite axial stroke of the shaft in each direction, said means comprising a pawl yieldingly held approximately at right angles to the
- 15 shaft, the shaft being provided with reversely disposed shoulders for engaging with the pawl near the opposite end of the axial movement of the shaft, said shoulders being arranged to release said pawl when
- 20 rotary movement is imparted to said shaft, and means actuated by the continued rotary movement of said shaft to move said pawl into an inclined position.
25. In a machine of the class specified, a registering train of counters, and means for resetting the said counters, including in combination a rotary and axially movable shaft provided with a collar, a spring actuated pawl pivoted adjacent to the said collar, and yieldingly held when free approximately at right angles to said shaft, the collar being provided with a shoulder for engaging with the said pawl, and with an inclined surface for swinging the pawl by the rotary movement of the collar.
26. In a machine of the class specified, a registering train of counters, and means for resetting the said counters, including in combination a rotary and axially movable shaft, means for compelling a definite axial stroke of the shaft in both directions, consisting of a spring-pressed pawl yieldingly held at approximately right angles to the shaft, the shaft being provided with reversely disposed shoulders for engaging with the pawl near the opposite ends of the axial movement of the shaft, and with an inclined surface for inclining the pawl by the rotary movement of the shaft.
27. In a machine of the class specified, a registering train of counters, and means for resetting the said counters, including in combination a rotary and axially movable shaft, means for compelling a definite axial stroke of the shaft in each direction, including a spring-pressed pawl and reversely disposed shoulders carried by the shaft for engaging with the pawl at different axial positions of the shaft, the said shoulders
- being extended circumferentially of the shaft, to maintain their engagement with the pawl during a portion of the rotation of the shaft.
28. In a machine of the class specified, a registering train of counters, and means for resetting the said counters, including in combination a rotary and axially movable shaft, means for compelling a definite axial stroke of the shaft in each direction, including a spring-pressed pawl and reversely disposed shoulders carried by the shaft for engaging with the pawl at different axial positions of the shaft, the said shoulders being extended circumferentially of the shaft, to maintain their engagement with the pawl during a portion of the rotation of the shaft, the shaft also being provided with a circumferentially extending inclined surface to reverse the pawl during the rotary movement of the shaft.
29. In a machine of the class specified, a registering train of counters, and means for resetting said counters including in combination a rotatable and axially movable shaft and means for compelling a definite axial stroke of the shaft in each direction, including a spring-pressed pawl yieldingly held at rest at right angles to the shaft, and a part carried by said shaft and having reversely disposed shoulders extending circumferentially of the shaft and arranged to engage the pawl in oppositely inclined positions thereof, said part being also provided with a circumferentially arranged inclined surface arranged to engage the pawl when the latter is in its right angular position and move it into an inclined position as said shaft is rotated.
30. In a machine of the class described, a registering train of counters, and means for resetting the said counters including in combination a swinging pawl, a rotatable and axially movable shaft provided with reversely disposed shoulders for engaging with the pawl in its oppositely inclined positions, said shoulders being arranged to be moved out of alinement with said pawl by the rotation of said shaft, and means for permitting the shaft to move axially when said shoulders are in alinement with said pawl and to prevent its axial movement in one direction when it is in other rotary positions.
31. In a machine of the class specified, a registering train of counters, and means for resetting the said counters, including in combination a rotary and axially movable shaft provided with reversely disposed shoulders extending circumferentially of the shaft, a resiliently held pawl for engaging with the said shoulders at oppositely inclined positions of the pawl to prevent axial movement of the shaft during a

portion of its rotation, and other means for preventing the said axial movement at other portions of its rotation.

32. In a machine of the class specified, a registering train of counters, and means for resetting the said counters, including in combination a rotary and axially movable shaft provided with reversely disposed shoulders extending annularly of the shaft, 10 a resiliently held pawl for engaging with the said shoulders at oppositely inclined positions of the pawl to prevent axial movement of the shaft during a portion of its rotation, the shaft being provided with 15 means engaging with a fixed portion of the machine to prevent the said axial movement of the shaft at other rotary positions.

33. In a machine of the class specified, a registering train of counters, and means for resetting the said counters, including in 20 combination a rotary and axially movable shaft provided with a shoulder extending annularly of the shaft, a resiliently held pawl for engaging with the said shoulder 25 to prevent axial movement of the shaft in one direction during a portion of its rotation, a bearing for the shaft provided with a splineway, a projection carried by the shaft and in register with said splineway when 30 the pawl is in engagement with the said shoulder, the said projection engaging against the end of the bearing to prevent the said axial movement of the shaft at its other rotary positions.

35 34. In a machine of the class specified, a registering train of counters, and means for resetting said counters including in combination a rotatable and axially movable shaft provided with means for preventing axial 40 movement except when in a certain rotary position and for preventing rotary movement except when in a certain axial position, and means for preventing its return axial movement until it is first rotated, including 45 a shoulder carried by the shaft and a pawl engaging with said shoulder when the shaft is near one end of its axial movement.

35. In a machine of the class specified, a 50 registering train of counters, and means for resetting said counters including in combination a rotatable and axially movable shaft provided with means for preventing axial movement except when in a certain rotary 55 position and for preventing rotary movement except when in a certain axial position, means for preventing its return axial movement until it is first rotated, including a shoulder carried by the shaft and a pawl 60 engaging with said shoulder when the shaft is near one end of its axial movement, and means for releasing the pawl when rotary movement is imparted to said shaft, whereby the shaft is free to return axially upon

being rotated to its axially movable position.

36. In a machine of the class specified, a registering train of counters, and means for resetting said counters including in combination a rotatable and axially movable shaft 70 provided with means for preventing axial movement except when in a certain rotary position and for preventing rotary movement except when in a certain axial position, and means for making it necessary to 75 rotate said shaft after it has been moved in one direction before it can be moved in the opposite direction.

37. In a machine of the class specified, a registering train of counters, and means for 80 resetting said counters including in combination a rotatable and axially movable shaft provided with means for preventing axial movement except when in a certain rotary position and for preventing rotary movement 85 except when in a certain axial position, means for making it necessary to rotate said shaft after it has been moved in one direction before it can be moved in the opposite direction, said means including a 90 ratchet and coöperating pawl, a shoulder carried by a shaft, and a pawl for engaging with the shoulder when axial movement has been imparted to said shaft, the last mentioned pawl being arranged to be released 95 by the rotary movement of said shaft.

38. In a machine of the class specified, a registering train of counters, and means for resetting said counters including in combination a rotatable and axially movable 100 shaft provided with means for preventing axial movement except when in a certain rotary position and for preventing rotary movement except when in a certain axial position, means for making it necessary to 105 rotate said shaft after it has been moved in one direction before it can be moved in the opposite direction, said means including a ratchet and coöperating pawl, a shoulder carried by a shaft, and a pawl for engaging with the shoulder when axial movement has been imparted to said shaft, said shoulder 110 extending less than the circumference of the shaft whereby the pawl is released when the shaft is rotated.

39. In a machine of the class specified, a registering train of counters, and means for resetting said counters including in combination a rotatable and axially movable shaft, means for preventing the rotation of 120 said shaft except at certain of its axial positions and for preventing the axial movement of the shaft except at certain of its rotary positions, and means for compelling the shaft when actuated to be moved first in a forward axial direction, then in a rotary direction, and then in a return axial direction, said means including reversely disposed cir- 125

cumferential shoulders extending less than the circumference of the shaft, a yielding pawl engaging with one of said shoulders near the forward end of the axial movement

5 of the shaft, and rotary means moving with the shaft for moving the pawl into a position to engage the other of said shoulders.

40. In a machine of the class specified, a rotary counter, means for stopping the 10 counter at its zero position, and means for rotating the counter to its zero position from all other of its rotary positions, said means including a dog rotatably mounted adjacent to the counter, means for imparting a complete rotation to the dog, and an arm mounted upon the counter and engaging with the dog to limit the movement of the latter relatively to the counter and having a yielding movement to permit a further movement of 15 said dog after the movement of the counter has been stopped.

41. In a machine of the class specified, a rotary counter, means for stopping the counter at its zero position, and means for 20 rotating the counter to its zero position from all other of its rotary positions, said means including a dog rotatably mounted adjacent to the counter, means for imparting a complete rotation to the dog, and a 25 spring-pressed arm pivotally mounted upon the counter and engaging with the dog to limit the movement of the latter relatively to the counter and having a swinging movement to permit a further movement of the 30 dog after the movement of the counter has been stopped.

42. In a machine of the class specified, a rotary counter, means for stopping the counter at its zero position, and means for 40 rotating the counter to its zero position from all other of its rotary positions, said means including a dog rotatably mounted adjacent to the counter, means for imparting a complete rotation to the dog, and an 45 arm mounted upon the counter and engaging with the dog to limit the movement of the latter relatively to the counter and having a yielding movement to permit a further movement of said dog after the movement 50 of the counter has been stopped, said dog being capable of axial movement to release said arm after said further movement of said dog.

43. In a machine of the class specified, a 55 rotary counter, a stop for checking the movement of said counter in a predetermined position, a dog, means for imparting rotation to said dog, an arm connected with said counter and arranged to be engaged by said dog to cause the counter to rotate

with the dog, said arm being yieldable to permit a further rotation of the dog after the movement of said counter has been stopped.

44. In a machine of the class specified, a 60 rotary counter, a stop for checking the movement of said counter in a predetermined position, a dog, means for imparting rotation to said dog, an arm connected with said counter and arranged to be engaged by said dog to cause the counter to rotate with the dog, one of said parts being yieldable to permit a further movement of said dog after the movement of said counter has been stopped. 70

45. In a machine of the class specified, a rotary counter, a stop for checking the movement of said counter in a predetermined position, a dog, means for imparting rotation to said dog, an arm connected with 80 said counter and arranged to be engaged by said dog to cause the counter to rotate with the dog, one of said parts being yieldable to permit a further movement of said dog after the movement of said counter has 85 been stopped, one of said parts being capable of axial movement to move said parts out of engagement after the further movement of said dog and to permit said dog to be moved into position in front of said arm 90 when said counter is in said predetermined position and to be moved into position in the rear of said arm when said counter has been moved from said predetermined position. 95

46. In a machine of the class specified, a rotary counter, a stop for checking the movement of said counter in a predetermined position, a dog, means for imparting rotation to said dog, an arm connected with 100 said counter and arranged to be engaged by said dog to cause the counter to rotate with the dog, said dog being axially movable into the plane of the arm in the rear of the same when the counter has been moved from said predetermined position, whereby it will engage the arm and move the counter to its predetermined position, and into the plane of the arm in front of the same when said counter is in said predetermined position, 105 whereby the movement of said dog will not actuate said counter. 110

In testimony whereof I have signed my name to this specification in the presence of two subscribing witnesses.

SAMUEL P. HUNTINGTON.
